CLAIM

The ornamental design for an overshoe, as shown and described.

DESCRIPTION

FIG. 1 is a top plan view of a overshoe showing my new design;

FIG. 2 is a side elevational view thereof;

FIG. 3 is a top plan view of an overshoe showing a modified form of my new design; and

FIG. 4 is a side elevational view thereof.

The bottom of both forms is plain and unornamented.

Fig. 1
